UNITED STATES PATENT OFFICE.

EMILE HOUTAIN, OF BRUSSELS, BELGIUM.

DESIGN FOR A DIAPHRAGM FOR TOBACCO-PIPES.

SPECIFICATION forming part of Design No. 21,552, dated May 17, 1892.

Application filed December 11, 1891. Serial No. 414,735. Term of patent 14 years. Patented in Belgium November 21, 1890, No. 92,808; in France April 7, 1891, No. 212,602, and in England April 13, 1891, No. 6,307.

To all whom it may concern:

Be it known that I, EMILE HOUTAIN, a subject of the King of Belgium, residing at Brussels, Belgium, have invented and produced a new and original Design for a Diaphragm or Separator for Tobacco-Pipes, (patented in Belgium, November 21, 1890, No. 92,808; in France, April 7, 1891, No. 212,602, and in Great Britain, April 13, 1891, No. 6,307,) of which the following is a specification, reference being had to the accompanying drawings, in which—

Figure 1 is a plan view of the diaphragm or separator, and Fig. 2 is a sectional vertical section of the same.

My design, as shown, consists, essentially, of a central concavo-convex portion B of inverted form and having perforations c, from which peripherally extend a series of outwardly-inclined vertical ears A of square form and tapering to an edge toward their outer portions, said ears extending in the direction in which the central portion is convexed.

I am aware of the construction of diaphragm or separator disclosed by German Patent No. 3,533, and do not wish to be understood as attempting to cover, broadly, anything therein set forth. My design will be readily distinguished from said prior construction in that the central portion has circular perforations and is almost hemispherical in shape, while the outer ears are not only square in shape, but taper to a knife edge. 25 35

I claim—

The design for a diaphragm or separator for tobacco-pipes, substantially as herein described and shown. 40

In witness whereof I have hereunto set my hand in presence of two witnesses.

EMILE HOUTAIN.

Witnesses:

W. R. KIRKPATRICK,
II. KIRKPATRICK.
